FLUID PROJECTOR

Thomas R. Hayner, United States Army, and
Theodore Loew, Baltimore, Md.

Application February 24, 1945, Serial No. 579,642

2 Claims. (Cl. 158—28)

(Granted under the act of March 3, 1883, as
amended April 30, 1928; 370 O. G. 757)

1

The invention described herein may be manufactured and used by or for the Government, for governmental purposes, without the payment to us of any royalty thereon.

This invention relates particularly to a weapon termed the "one-shot flame thrower" developed to meet the need in the field for an inexpensive lightweight flame thrower.

An object of this invention is to provide a portable flame thrower having various tactical uses in combat, especially when it is unsuitable to use the conventional flame thrower which is carried on the back of a soldier.

Another object is to provide a weapon which may be made to function as an emplacement for projecting a liquid chemical agent with an effective range.

A further object is to provide a projector which functions automatically or semi-automatically.

Accomplishment of the above and further objects will become apparent from the following description.

The chemical agent projector provided by this invention involves the principle of actuating a piston by gas pressure developed inside a tubular barrel for the purpose of forcing a liquid chemical agent through a nozzle in a discharge assembly at one end of the barrel. Gas pressure required to actuate the piston may be generated from a pyrotechnic solid material or may be developed from a liquefied or highly compressed gas by a propelling charge assembly. The functioning of the apparatus may be initiated manually where the apparatus is in position for operation, by remote control or by an automatic delay device, because following the initiation of the operation, the apparatus is capable of functioning automatically to eject a stream of chemical agent a substantial distance. Means are provided to obtain a substantially complete discharge. Also, means are provided for obtaining automatic ignition of an incendiary agent.

A practical embodiment of the weapon in the form of a one-shot flame thrower is illustrated in the accompanying drawing, wherein

Figure 1 shows a longitudinal cross section view of the body assembly; and

Figure 2 shows a longitudinal cross section view of the discharge assembly as attached to the discharge end of the body assembly in the one-shot flame thrower.

Figure 3 shows a relatively enlarged and detailed cross section of a fuse igniter suitable for use in the discharge assembly.

Figure 4 shows a longitudinal cross section view

of an alternate form of discharge assembly with details on an alternate form of igniter.

The body assembly comprises primarily of the sheet steel barrel 1 which contains filling chamber 2, houses a propelling charge assembly, and serves as the cylinder for the piston 3. This cylindrical barrel having an inside diameter of about 4½ inches tapers down at the front, at about a 45-degree angle, to a 1½-inch opening 4. Internally-threaded adaptor socket 5 is welded to this opening, and into this adaptor socket 5 is screwed a pressure disc adaptor 6 of the discharge and ignition assembly. The back of the cylindrical body is open and flanged to receive an asbestos gasket 7 and a flanged, sheet steel, body cover 8. The body cover 8 is bolted to the body 1 by 12 quarter-inch bolts 9. Through a hole centered in the body cover 8 is welded the bottle support 10 which contains the firing pin 11 and the firing pin spring 12. A retaining pin 13 passes through the bottle support 10 and the firing pin 11, perpendicular to their long axes, in order to hold the firing pin back against the pressure of the firing pin spring. A finger ring 14 passes through the retaining pin 13 to facilitate withdrawal of the retaining pin 13 when the flame thrower is fired. The enlarged portion of the bottle support 10, inside the body cover 8, has a sleeve 15 which is threaded internally to receive the external threads on the mouth of a steel carbon dioxide bottle 16 similar to the bottle used by the Air Forces on life rafts. Between the point where the bottle support is welded to the body cover and the point where the internal threads on the enlarged portion of the bottle support begin, four ½-inch holes 17 through the wall of the bottle support serve as gas ports.

The propelling charge assembly comprises primarily the steel bottle 16, which contains the liquid carbon dioxide used as propelling charge in this flame thrower. Into the mouth of the bottle 16 is seated a thin, frangible, metal disc 18 which is held in place by an externally-threaded retainer 19 screwed into the internal threads on the mouth of the bottle. Other types of compressed gases may be used.

The piston assembly comprises primarily the hollow cylindrical sheet steel piston 3 with an outside diameter of approximately 4½ inches to 50 slip fit inside the cylindrical flame thrower body 1. The back 20 of the piston is open; consequently, the piston can be drawn to the back of the flame thrower body 1 without interference with the propelling charge assembly. Three ¾-inch prongs 21 projecting from the back of the

piston wall have curved lips to fit into the $\frac{1}{2}$ -inch-radius curve at the flange of the flame thrower body. A packing 22 of suitable material such as soft felt may be placed in a recess enclosing piston 3 to make a more fluid tight seal against leakage of liquid agent past the piston. The front of the piston tapers at about 45-degree angle down to an opening which conforms with the tapered shape of barrel 1 at its discharge end. The body 23 of a relief valve is welded to the inside of the piston wall at the front opening of piston 3 and the stem 24 of the relief valve protrudes through the $\frac{1}{16}$ -inch opening. A relief valve spring 25 seated in a retainer 26 which is screwed into the back of the valve body 23, holds the valve disc 27 forward against the tapered walls of the valve body 23, thus closing off the T-shaped port 28 in the stem 24 of the relief valve. The retainer 26 in which the relief valve spring 25 is seated has a port 29 in the center through which the residual pressure passes when the relief valve is open.

The discharge and ignition assembly comprises primarily a cylindrical sheet metal shield 30 which serves both as a house for the fuzees 31 and as a shield in which the fuel is ignited after it is propelled from the cylindrical body of the flame thrower. The pressure disc adaptor 6, screwed into the adaptor socket 5 on the flame thrower body 1, joins the ignition assembly to the body assembly. A $\frac{1}{4}$ -inch nozzle-like orifice 32 through the pressure disc adaptor serves as a nozzle through which the stream of fuel is propelled into the cylindrical shield 30 that houses the fuzees. A frangible aluminum pressure disc 33 seated in the pressure disc adaptor 5 seals the fuel in the flame thrower body before the flame thrower is fired. This pressure disc 33 is held in place by a retainer at the back end of the cylindrical shield 30 which screws into the pressure disc adaptor 5. Two pull-wire fuzees 31 are fastened, diametrically opposite, along the walls of the cylindrical shield, with their pull-wires 34 extending toward the front of the cylindrical shield 30. A hollow sheet metal piston 35 is slip fitted into the front of the cylindrical shield. The pull-wires 34 of the fuzees 31 pass through holes in this piston and are tied together, with as little play as possible, after the piston 35 has been inserted into the cylindrical shield 30.

Each of the fusee ignitors 31 as illustrated in detail by Fig. 3 comprises a tubular member 38 to the rear end of which is securely fixed a wood plug 39 by a wire staple 40. A cardboard tube 41 secured to a narrowed neck of the wood plug serves as a container for a burning composition 42 and an igniting composition 43. The burning composition 42 may be of a commercial type such as used in signaling fuses, e. g., containing potassium chlorate, carbon, and sulfur. The igniting composition 43 may be a mixture of potassium chlorate and finely divided carbon. A scratcher material containing red phosphorus with lacquer and an abrasive, such as ground silica, acts as a coating on the coating 44 on an end portion of a pull wire 34 to complement the igniting mixture 43 for firing the mixture 43 when fractionally engaged therewith upon moving of the pull wire 34. A spot of solder 45 at a kink in the wire 34 prevents the wire from being pulled through the block 46 which is mounted on the wire 34. A water-proofed paper seal 47 envelops the fusee for water-proofing

and is also in contact with the wire 34 where it enters the fusee.

Each fusee is secured to the shield 30 by a bolt 48 through a hole 49 in the wood plug. When the fusee is in position for functioning, upon the outward movement of the piston 35, the pull wires 34 upon being pulled outwardly cause the scratching and burning of the igniting mixture 43, and the wood plugs 46 simultaneously rupture and tear away the conical portion of the waterproofing seal 47 so that flame from the burning composition 42 can be ejected outwardly for ignition of discharging fuel from chamber 2. The piston 35 becomes completely ejected by the pressure of the discharging fuel filling.

In the alternative form of the igniting means shown by Fig. 4, a tubular housing 38 contains a suitable ignitor cap 50, such as a 45 caliber pistol blank cartridge inserted in the open end, a firing pin 51, and a coil spring 52. The firing pin 51 is aligned with primer portion 53 in the cartridge 50, and the coil spring 52 under compression forces the firing pin into the primer 53 when an obstructing retaining pin 54 is withdrawn to allow movement of the firing pin. A retaining clip 55 holds the cartridge and tubular housing 38 in place. The retaining pin 54 may be fashioned to be withdrawn manually or to be withdrawn automatically by a pull wire arrangement such as described with reference to Fig. 2 and Fig. 3.

In functioning, when the flame thrower operator grasps the finger ring 14 and pulls the retaining pin 13 out of the bottle support 10, the firing pin 11 inside the bottle support 10 is freed and moves forward under the pressure of the firing pin spring 12. When the firing pin moves forward, the point of the firing pin ruptures the thin, frangible disc 18 in the mouth of the bottle that contains the propelling charge. The diameter of the firing pin is larger than the diameter of the hole through the retainer which holds the frangible disc in the mouth of the bottle; consequently, the firing pin enters the mouth of the bottle no farther than is necessary for the point of the firing pin to rupture the frangible disc. If desired, the retaining pin may be pulled from the emplaced apparatus by means of a lanyard.

Where the frangible disc in the mouth of the bottle is ruptured, the propelling charge of liquid carbon dioxide vaporizes, and the consequent pressure forces the firing pin 11 back. The expanding gas can then pass through the four $\frac{1}{8}$ -inch ports 17 in the wall of the bottle support and thus enter the cylindrical body of the flame thrower, behind the hollow piston 3.

When pressure is exerted by the expanding gas behind the piston, the three prongs 21 that hold the piston to the back of the flame thrower body are flexed inward, freeing the lips of the prongs from their fit against the curved part of the body flange, and thus permitting the piston to move forward against the fuel contained in the flame thrower body in front of the piston. The pressure of the piston on the fuel ruptures the aluminum pressure disc 33 that is seated just in front of the nozzle-like orifice 32 in the pressure disc adaptor, and the entire fuel charge is ejected in a stream through this nozzle-like orifice in the pressure disc adaptor.

With the initial surge of the fuel stream in the cylindrical shield that houses the fuzees, the piston 35 in the shield is forced out the front of the shield. Since the pull-wires 36 of the two

fuzees 31 are fastened to this piston, the forward movement of this piston fires the fuzees. The balance of the fuel charge is ignited by these fuzees as the fuel passes in a stream through the cylindrical shield.

In expelling the complete fuel charge, the piston 2 in the flame thrower body moves forward until the relief valve stem 24, which protrudes from the tapered front of the piston, strikes against the shoulder of the pressure disc adaptor. After the forward movement of the relief valve stem is checked by the pressure disc adaptor 6, the piston 2 continues to move forward until the relief valve spring 25 is completely depressed. In depressing the relief valve spring, the relief valve body, which is welded inside the tapered front of the piston, has moved forward so that the T-shaped port 28 in the stem of the relief valve now clears the wall of the relief valve body. With the relief valve open in this manner, the residual pressure behind the piston 2 is then discharged through the T-shaped port 28 and out through the nozzle-like orifice 32 in the pressure disc adaptor 6.

Wire clamps 57 may be welded to body 1 for aiding in carrying of the apparatus with straps passed through these clamps.

In using the projector as a one-shot flame thrower, the filling 2 may be a thickened or gelled gasoline or naphtha mixture of a type hitherto employed as flame thrower fuels. A suitable gelled gasoline of proper consistency comprises a 4% mixture of soaps, such as aluminum oleate, aluminum stearate, aluminum naphthenate and aluminum soaps of coconut oil fatty acids. Other suitable liquid flame thrower fuels may be formulated by thickening naphtha hydrocarbons with substances such as rubber, synthetic polymers like isobutyl methacrylate, asphalt, resins and the like. Results of tests indicate that effective ranges of about 40 to 50 yards or more may be expected with fuels of proper consistency. The projector may also be used to project various other liquid chemical agents such as liquid vesicants, e. g., liquid mustard (dichloroethyl sulfide).

The liquid agent projector may be designed to have gas pressure developed for actuating the piston by firing a slow burning powder with remote control by electrical ignition. The firing pin may be released automatically by a chemical or mechanical delay device.

Accordingly, the liquid agent projecting apparatus may be operated for many purposes, e. g., for attacking a pill box, for defending a road block, or as a substitute for land mines. It also finds use as a highly devastating sabotage weapon.

Although specific shapes, dimensions and materials have been described in explanation of the illustrated embodiment, variations may be made in such details without deviating from the principles of the invention.

It is to be understood that various modifications

come within the spirit and scope of the invention as defined in the appended claims.

We claim:

1. A liquid agent projector, including a tubular shield, a container having a tapered front portion, and a centrally perforated adapter plug portion rigidly securing said front portion and said shield together and being provided with a rupturable diaphragm adapted to be torn by fluid pressure generated in said container, said tubular shield having a slidably mounted piston, a fuse secured to the shield intermediate of said piston and said plug, having a frictionally ignitable portion and a wire ignition means in frictional contact with said ignitable portion and having one of its end portions secured to said piston in a manner whereby the ignition wire will be pulled and ignite the ignitable portion when the shield piston is moved away from said fuse, a compressed fluid receptacle rigidly secured to the rear portion of said container and sealed by a rupturable diaphragm, a spring pressed firing pin mounted in a tubular casing, said tubular casing being perforated within said container and extending therethrough and having a locking pin engaging said firing pin outside of said container, said firing pin means being adapted to puncture the diaphragm of the compressed fluid receptacle when the locking pin is removed from the firing pin, said container having intermediate of its front portion and the compressed fluid receptacle a slidably mounted liquid sealed piston serving as a movable partition dividing said container into two variable capacity compartments, the front one of which is adapted to contain a liquid agent, and the rear one of which is adapted to receive the compressed fluid after the diaphragm of the compressed fluid receptacle has been punctured by the firing pin.
2. The liquid agent projector of claim 1, in which the container piston is tapered forwardly and is provided with a pressure release valve adapted to open when a difference in fluid pressure in the front and rear compartments of said container exceeds a predetermined amount.
